UNITED STATES PATENT OFFICE.

JOHN E. BELL, OF BROOKLYN, NEW YORK, ASSIGNOR TO SINCLAIR REFINING COMPANY, OF CHICAGO, ILLINOIS, A CORPORATION OF MAINE.

OPERATION OF OIL STILLS.

Application filed August 10, 1923. Serial No. 656,672.

To all whom it may concern:

Be it known that I, JOHN E. BELL, a citizen of the United States, residing at Brooklyn, in the county of Kings, State of New York, have invented certain new and useful Improvements in the Operation of Oil Stills; and I do hereby declare the following to be a full, clear, and exact description of the invention, such as will enable others skilled in the art to which it appertains to make and use the same.

This invention relates to an improved method of operation of oil stills, and particularly of oil cracking stills, and involves an improved method of heating of the stills whereby danger of overheating is avoided or minimized and a more uniform heating action is obtained.

The invention relates particularly to improvements in the heating of pressure stills for cracking hydrocarbons of high boiling points such as gas oil and the like, to form more volatile or lighter hydrocarbons such as those which constitute commercial gasoline.

Among the objects of the invention are the protection of the tubes or heating surfaces of the still from overheating or burning, the lengthening of the time of the runs between cleaning, with a corresponding increase in the distillate produced, a more uniform distribution of the heat throughout the heating chamber and other advantages which will appear from the following description.

Pressure stills and other stills for cracking oil are heated by furnaces in which coal, gas, or oil is burned, and, for economy in fuel consumption, it is desirable that the fuel be burned in the furnace with the least amount of excess air and the maximum furnace temperature. Excessive temperatures are, however, objectionable in the heating chambers of oil cracking stills. Carbon is formed during the cracking operation and tends to deposit on the side of the tubes or heating surfaces of the still and such a layer of carbon or of heavy tar is a poor conductor of heat and insulates the metal surface from the oil on the inside, with the result that the temperature of the metal increases over the temperature of the oil, the amount of this increase being proportional to the thickness of the carbon deposit and to the amount of heat delivered to the external surface heated by the furnace gases.

The overheating of the still or of the tubes or heating elements of a cracking still and the resulting increased tendency of carbon formation, tend to give hot spots and involve a considerable element of danger or hazard to life and property due to the possible bursting of a tube which has become overheated and burnt. Inasmuch as the pressure in cracking stills is frequently maintained at pressures approximating 100 pounds per square inch and may be maintained considerably higher, any break or rupture is followed by a disastrous fire.

In an oil cracking still the tubes or other heating surfaces most exposed to the heat of the furnace will be the first to suffer. The danger of overheating of such tubes or surfaces can be decreased by reducing the fuel consumption, but this in turn reduces the capacity of the still; while, if the still is driven hard to increase its capacity by increasing the fuel consumption, the danger of overheating is greatly increased.

According to the present invention the heating of the still is modified and regulated to avoid or greatly reduce the danger of overheating.

According to the present invention the products of combustion from the firebox are cooled by admixture with hot gases at a lower temperature prior to bringing them into contact with the tubes or other heating surfaces of the still, thereby reducing the temperature to which the first tubes or surfaces are subjected and the amount of heat absorbed by them, and increasing the amount of heat absorbed by the tubes or surfaces over which the gases pass before escaping from the heating chamber. This cooling of the products of combustion is nevertheless effected without sacrificing either fuel economy or capacity of the still, and may even result in a considerable increase in still capacity.

With the ordinary arrangement of furnace, such as commonly used under stills, a large proportion of the heat in the fuel passes directly from the fuel-bed, where solid fuel is used, or from the flame and hotter brick work, when gaseous or oil fuel is used, direct to the heat absorbing surface of the still by radiation. It has been shown by tests that the amount of heat absorbed by the tubes next to the fire, in the case of a steam boiler, may be and usually is 40 or 50

times as great as the average absorption of heat throughout the whole surface, and this amount of heat is principally transferred as radiant energy. It has also been shown that 5 heat transferred in this way increases very rapidly with the furnace temperature; the process in general being controlled by Stefan's law for radiation which makes the total amount of radiation proportional to the fourth power of 10 the absolute temperature of the radiant. When the furnace is arranged so that the heat absorbing surfaces are shielded from direct radiation, such shields and the gas 15 connecting passages become secondary radiators and the total amount of heat transmitted in this way is greatly reduced; but the heat that would otherwise be transmitted by radiation is absorbed by the gases 20 with the result that there is an actual increase in gas temperature of the gases coming in contact with the heating surfaces of the still, although this increase in gas temperature does not compensate for the reduction 25 in the radiant heat.

According to the present invention the heat absorbing surface of the cracking still is protected from the direct radiation of the furnace by the interposition of a high 30 bridge wall and by providing a vertical flue with refractory walls, or by other suitable arrangement of the fire box and heating chamber.

Also, according to the present invention, 35 the products of combustion from the furnace are diluted and cooled with a heated gas before they are passed over the oil heating surfaces. For example, I may introduce a diluting body of air or gas into the 40 connecting flue, between the furnace and still, at a point near the furnace. The addition of such a diluting body of air or gas reduces the gas temperature where the gases first contact with the heating surfaces of the 45 still, and also the temperature of the refractory walls. The heat absorbed by the surface or surfaces of the still first in contact with the furnace gases is thus reduced in two ways; namely, by the lower temperature 50 of the gas and second, by a reduction in the temperature of the refractory secondary radiating surfaces.

If the diluting gas is not heated, the obvious result is a reduction in efficiency such 55 as accompanies the burning of fuel with an excessive amount of cold air. According to the present invention, however, the diluting gas admixed with the products of combustion is heated, for example, to approximately 60 the temperature of the waste gases leaving the heating chamber of the still. I have found that if the temperature of the diluting gas is approximately that of the waste gases leaving the still surface, not only is there no reduction in the fuel econ-

omy and capacity, but on the other hand, there is a slight increase in both.

Accordingly, in the preferred embodiment of the invention, I recycle a part of the heated gases from near the outlet of the 70 heating chamber and introduce them into the fire box or bring them into admixture with the products of combustion, so that the products of combustion are cooled and diluted thereby before they are passed over 75 the oil heating surfaces. The introduction of the recirculated flue gas reduces the temperature of the furnace gases to a point where objectionable overheating can be avoided, while, as these recirculated gases 80 are at the temperature of the gases leaving the heating chamber, the fuel efficiency is not decreased.

The present application is in part a continuation of my prior application, Serial 9 No. 532,482, filed January 28, 1922, for "oil heating furnaces" and the improved process of the present invention can advantageously be carried out in apparatus such as described and claimed in such prior application. Thus, as described in said prior application, in one method of operation, the dilutant gas admixed with the products of combustion may be a proportion of the waste 95 gas at the temperature at which it leaves the heating chamber of the still, this waste gas being drawn aside and returned to the furnace for admixture with the products of combustion. According to another method 100 of procedure, air may be preheated by heat interchange with the escaping products of combustion from the heating chamber and the preheated air may be admixed with the products of combustion. An air heater may 105 be installed in the flue leading from the still and air forced through this heater and preheated therein and then utilized as a diluting medium by forcing it into the flue between the furnace and still.

In its broader aspects, accordingly, the invention provides an improved method of operation in which the products of combustion are diluted and cooled with heated gases at a lower temperature, and particularly with 110 gases of approximately the temperature of the flue gases leaving the still chamber and passing to the flue or stack. This reduction in temperature prevents the high temperatures of the fire box from overheating the first tubes or surfaces of the still and there is a decrease in the quantity of heat absorbed by these initial heating surfaces with an increase in the quantity of heat absorbed by the remaining surfaces. A more uniform 115 distribution of the heating action is thus accomplished, while the increased volume of the heating gases results in an increase of velocity which increases the rate and efficiency of heat absorption and has the further desirable result of carrying soot and 120

slag through the heating chamber rather than depositing them upon the heating surfaces.

The preheating of air by the flue gases and the utilization of the preheated air for admixing with the products of combustion tends to give an oxidizing atmosphere in the heating chamber of the still; and I consider it more advantageous to recycle a part of the flue gases than to preheat air and utilize the preheated air for admixture with the products of combustion. This recycling of part of the flue gases requires little added equipment and little modification of the furnace construction. The recycled gas for example, may be returned through openings or flues in the walls, floor or lining of the furnace, and, in addition to admixing with and cooling the gases from the fire box may also serve to cool the walls or floors or may be introduced so as to protect the furnace arch or other parts of the furnace from the intense heat of combustion.

When the same amount of fuel is burned in the furnace, with recycling of part of the flue gases, as when the gases are not recycled, it is evident that a measure of the efficiency and capacity of the oil can be made from the temperature and weight of the waste gases. The weight of the gases is not however changed by the recycling of part of the gases, but experience has shown that the temperature of the waste gases escaping to the stack is actually reduced by the recycling of a portion of them. As a result, the efficiency and capacity of the still are somewhat increased.

The increase of the rate of gas flow over the heating surfaces, while it increases the rate and efficiency of heat absorption, also increases the friction loss and to maintain the same furnace draft it is necessary to have a somewhat increased draft at the still outlet. When this is provided however, not only will the capacity of the still be maintained but the efficiency will be somewhat increased, while, on account of the lower temperature of the gases striking the first tubes or heating surfaces of the still, these surfaces will be protected, in the manner previously described.

The invention is of more or less general application for the heating of oil stills, and particularly of tubular oil cracking stills where the oil is circulated through tubes passing through the furnace, for example, where the oil is circulated upwardly through vertical tubes or where the oil is circulated through horizontal tubes extending through or arranged in the heating chamber.

In a tubular oil still the circulation of the heating gases is advantageously countercurrent, or in a general countercurrent direction, to that of the oil. Where, for example, the oil is circulated upwardly or in a gen-

eral upward direction through a tubular still, or through the tubular heater of a still, the gases are circulated on a general downwardly direction; and the present invention is of particular value for use with such a tubular cracking still. In such a still, the oil is heated in its upward flow and is hottest in the upper tubes or in the upper portions of the tubes. Where the high temperature products of combustion are introduced into the top of the heating chamber containing such tubes, the tubes containing the hottest oil are subjected to the greatest heat. According to the present invention, the excessive temperatures of combustion are moderated and the products of combustion are cooled before they are brought into contact with the tubes or portions of tubes containing the hottest oil. The more uniform distribution of the heating gases gives an increased heating effect in the lower tubes or in the lower portions of the tubes so that in general a more uniform heating of the oil flowing through the tubular heater is accomplished, as well as the avoiding of excessive over-heating of any portions of the tubes.

The invention will be further described in connection with an oil still such as that described and illustrated in Patent No. 1,285,200, granted to the Sinclair Refining Company, November 19, 1918, on the application of Edward W. Isom; but it will be understood that the invention is of more general application, although it is of particular value with a tubular cracking still of the character referred to in said patent.

In the accompanying drawings I have shown certain forms of apparatus in which the process of the invention can be practiced, and the invention will be further described in connection therewith. It is to be understood however that these specific illustrations and descriptions are for the purpose of exemplification and that the scope of the invention is defined in the following claims, in which I have endeavored to distinguish it from the prior art so far as known to me, without, however, relinquishing or abandoning any portion or feature thereof.

In the oil cracking stills illustrated more or less conventionally in the drawings, the products of combustion coming from the fire box are tempered by an admixture of hot products of combustion which have been more or less cooled by circulation through the heating chamber in contact with oil tubes therein.

In the accompanying drawings, Figures 1, 2 and 3 show somewhat similar views of the heater of an oil cracking still of the general construction illustrated in said Patent No. 1,285,200, these three figures showing somewhat modified constructions and arrangements for recycling the flue gas or waste gas. It will be understood that

only the heater portion of the cracking still is shown, the main bulk supply tank containing the greater portion of the charge of the pressure still being arranged away from the furnace and the oil being circulated from said bulk supply tank through the heating tubes and back to the bulk supply. That is, the construction illustrated is one in which the oil is recirculated through heating tubes, 10 as distinguished from a tubular still or heater in which the oil is heated by a single pass therethrough; although the invention in its broader aspects is of general application to tubular and other cracking stills of various types and designs including single 15 pass tubular stills.

In the accompanying drawings the corresponding parts of the three figures are indicated by the same reference characters.

20 Referring to the drawings, the furnace illustrated comprises a fire box 1, which may be of any usual or preferred form, communicating by an elongated throat 2 with the heating flue or chamber 3 containing 25 the oil heating tubes. The chamber 3 is of considerable vertical length and communicates at its lower end with a stack flue 4. In Figs. 1 and 3 I have shown the fire box as equipped at 5 with a mechanical stoker 30 and in Figs. 1 and 2 with burners by means of which oil or gas may be used as fuel. The elongated throat 2 is separated from the heating flue or chamber 3 by a lengthy bridge wall 6 which, in Fig. 1, overhangs at 35 its top as at 30 into the throat of the fire box. The purpose of the elongated throat, and of the overhanging bridge wall in Fig. 1 is to shield the tubes in the heating flue from direct radiation from the fire box.

40 The battery of heating tubes 7 is connected at top and bottom to headers 9, 12, respectively, both of which headers are outside the heating flue. The tube 7 extends through an opening 8 in the top wall of the 45 furnace which is closed by a perforated slab 8^a of the refractory material through which the tubes extend. At their lower end the tubes 7 extend through a slab or slabs of refractory material 10 beneath which the 50 header 12 is located. The slabs of refractory material may rest upon collars formed on the tubes as shown in Fig. 1, and the plates or slabs 10 may rest upon angle irons 13 at their edges. The entire battery of 55 tubes is sustained from the top header so as to be free to expand and contract with change of temperature.

The lower header is connected to a manifold 12^a which receives oil through the pipe 60 12^b. The upper header is connected to a manifold 9^b which in turn connects with a pipe 11. The oil received through pipe 12^b enters the header 12, flows upward through the bank of tubes to the upper header and thence through the manifold and pipe 11.

When the heater is employed in a system of the type shown in the Isom patent to which reference has been made, the pipes 11, 12^b are connected to the bulk supply tank (not shown) and preferably one or 70 both of them are provided with means for accelerating the circulation as shown in said patent.

The heating flue is provided with baffles 14, 15 which cause the hot gases to pass back 75 and forth among the tubes of the battery a number of times, before reaching the stack flue 4 by which they make their exit. By reason of this thorough circulation among 80 and contact with the oil heating tubes, the heat is efficiently extracted from the products of combustion before they reach the stack flue. The efficiency is further increased due to the fact that the general direction of the flow of the heating gases and oil is opposed 85 so that the relatively cool oil entering at the bottom of the tubes extracts the heat from the partially cooled gases and its temperature increases until it is at the maximum in the upper pass of the furnace where 90 it is exposed to the gases fresh from the fire box. The oil heating tubes are however screened from direct radiation from the fire box, even at their upper ends, thus preventing 95 overheating with consequences to which reference has heretofore been made.

In order to reduce the temperature of the hot products of combustion coming from the fire box before they strike the oil containing tubes I provide means for returning a 100 portion of the partially cooled gases from the exit end of the heating chamber and for mixing it with the fresh products of combustion from the fire box. For this purpose I provide a return flue or flues 16 on one or 105 both sides of the furnace which connect with the lower end of the heating chamber at 17 and with a transverse flue or box 18 extending across the throat of the fire box. This flue is formed with a longitudinal opening 110 or openings 19 communicating with the throat of the furnace. A forcing means of any desired or well known character is interposed in each of the flues 16. In the construction illustrated a common Venturi construction is shown with a steam jet indicated at 28, but it will be evident that a positive 115 blower or other positive forcing means may be similarly used. By suitably controlling the forcing means any desired proportion of 120 the products of combustion may be returned and intermingled with the hot products of combustion rising from the fire box. By this means, as above pointed out, I am enabled to 125 temper the hot gases to any point desired, prevent overheating of the tubes at the upper pass and particularly the front tubes thereof, without reducing the thermal efficiency of the furnace. By thus returning a 130 portion of the products of combustion the

volume of gases in contact with the tubes and consequently the rapidity of flow is increased, and, therefore, the heating effect is improved and at the same time the heat is more evenly distributed throughout the tubes and throughout the length thereof.

In the construction of Fig. 2 the flue gases are in part admitted through a series of apertures or an elongated slot or flue 32 at the base of the bridge wall and in part introduced through a separate flue 30 provided in the floor of the furnace in order to cool the same. These gases entering through the flue 30 escape in the form of a protective blanket along the inner front wall of the furnace and over the arch 27, while the gases entering through the flue 32 tend to pass up along the bridge wall and to protect the bridge wall, although intermixture of the products of combustion and of the recycled flue gas will take place such that gases of an approximately uniform composition will pass over the bridge wall into contact with the tubes.

It will be evident that the amount of flue gases recycled can be varied and the temperature of the combustion gases correspondingly modified before they reach the tubes through which the oil is circulated.

The temperature in the fire box may for example, be maintained around 2400° F. and this temperature may be reduced by admixture of recycled flue gas for example, to a temperature of about 2000° F. before the

gases reach the tubes. In their passage through the first pass of the heating chamber the gases may be reduced from about 2000° to about 1300° F. to which temperature they enter the second pass where

they may be reduced to about 1000° F. The gases finally leaving the lower pass may be reduced to about 800° F. at which temperature a part of the flue gas is recycled for admixture with the hot combustion gases and the remainder is discharged at the stack.

The regulation of the recycling of the flue gases is independent of the rate of combustion in the fire box, and, with a sufficient recycling of flue gases, the rate of combustion may be somewhat increased without objectionable overheating of the surfaces of the cracking still by the admixed gases.

In practice there is usually a small leakage of air through the furnace structure and past the baffles 8^a and 10 into the heating chamber which results in the introduction of a certain amount of free oxygen into the furnace gases. This oxygen will be heated by the gases in the furnace chamber and may serve to bring about added combustion.

It will thus be seen that the present invention provides for the reduction of the furnace temperature of the heating gases at the point where they first come in contact

with the surfaces of the cracking still and that this reduction of temperature permits a milder condition of heat absorption in these tubes with resulting less coke formation, while the reduction of temperature in the furnace by re-circulation of gases protects the brick work and prevents slagging of the same. The fast velocity of gases past the tubes tends to prevent the deposit of furnace slag and dust upon the tubes with resulting impairment of vision of the tubes and heat conductivity.

It will further be seen that these and other advantages are obtained without sacrifice of the efficiency of the furnace but that the efficiency is somewhat increased, as well as giving a more uniform application of heat to the oil heating surfaces. As a result, the life of the heating tubes or elements is greatly increased, while the danger of injury from overheating and burning is greatly reduced, and the apparatus can be operated for longer periods of time without requiring shutting down for cleaning. The furnace linings are also prolonged because of the lower temperature of the gases which are brought in contact therewith.

It will further be seen that the recycling of flue gases is advantageously combined with an operation in which direct radiation upon the oil heating tubes is prevented by causing the combustion to take place in a fire box remote from the heating chamber and interposing a bridge wall or similar obstruction to cut off direct radiation.

While the invention is of more or less general application to oil stills, and particularly to tubular stills, it is of special value in oil cracking stills operated at a high pressure where there is tendency for carbon deposits to form on the heating surfaces and where the failure of any part of the still is accompanied with great hazard to life and property. In a tubular oil cracking still the invention makes the heating of the tubes more uniform, increases the efficiency of heat transfer, and decreases or removes altogether the danger of over-heating; while nevertheless taking full advantage of the heat of the furnace gases utilized in heating the still.

I claim:

1. The improvement in the heating of oil cracking stills in which oil is heated to the cracking temperature by hot products of combustion from a furnace passing externally over the oil heating surfaces of the still, which comprises recycling over the oil heating surfaces in admixture with fresh products of combustion from the furnace a portion of the hot waste heating gases which have previously passed over the heating surfaces.

2. The improvement in the heating of oil

cracking stills in which oil is heated to the cracking temperature by heat transferred to the oil through heating surfaces from hot products of combustion passing over the oil 5 heating surfaces from a furnace in which fuel is burned, which comprises diluting the hot products of combustion from the furnace with hot waste heating gases which have passed over the heating surfaces and passing 10 the resulting admixed heating gases over the oil heating surfaces.

3. The improvement in the heating of oil cracking stills in which oil is heated to the cracking temperature by hot products of 15 combustion from a furnace passing externally over the oil heating surfaces of the still, which comprises diluting the hot products of combustion from the furnace with hot gas at a lower temperature prior to 20 bringing said hot products of combustion into heat interchanging relation with the oil heating surfaces.

4. The improvement in the heating of oil cracking stills in which oil is heated to the cracking temperature by hot products of 25 combustion from a furnace passing externally over the oil heating surfaces of the still, which comprises diluting the hot products of combustion from the furnace with 30 gases at a temperature approximately equal to the temperature of the admixed gases after contact with the heating surfaces of the still.

5. The improvement in the heating of oil 35 cracking stills in which oil is heated to the cracking temperature by hot products of combustion from a furnace passing externally over the oil heating surfaces of the still, which comprises diluting the hot products 40 of combustion from the furnace with part of the hot waste heating gases from the still and passing the resulting mixture of gases over the oil heating surfaces.

6. The improvement in the heating of oil 45 cracking stills in which oil is heated to the cracking temperature by hot products of combustion from a furnace passing externally over the oil heating surfaces of the still, which comprises diluting hot products 50 of combustion from the furnace with hot gases at a lower temperature before passing them over the oil heating surfaces and also protecting the oil heating surfaces from direct radiation from the furnace.

55 7. The improvement in the heating of oil cracking stills in which oil is heated to the cracking temperature by hot products of combustion from a furnace passing externally over the oil heating surfaces of the still, 60 which comprises recycling a part of the hot waste heating gases which have passed over the heating surfaces, admixing them with hot products of combustion from the furnace and passing the resulting mixture over 65 the oil heating surfaces.

8. The improvement in the heating of tubular oil cracking stills in which oil is heated to the cracking temperature by hot products of combustion from a furnace passing externally over the tubular oil heating surfaces of the still, which comprises recycling a part of the hot waste heating gases from the still, admixing them with the hot products of combustion from the furnace to give a gaseous mixture of temperature lower than 70 the furnace gases before passing the heating gases over the tubular heating surfaces, and passing the gaseous mixture over the tubes of the tubular still. 75

9. The improvement in the heating of tubular oil cracking stills in which oil is heated to the cracking temperature by hot products of combustion from a furnace passing externally over the tubular oil heating surfaces of the still, which comprises circulating the oil and the heating gases in a general countercurrent direction and diluting the hot products of combustion with gas at approximately the temperature of the hot waste heating gases before circulating the 90 gaseous mixture over the heating tubes. 95

10. The improvement in the heating of tubular oil cracking stills in which oil is heated to the cracking temperature by hot products of combustion from a furnace passing externally over the tubular oil heating surfaces of the still, which comprises passing the heating gases in a generally downward direction over the tubular heating surfaces of the still, and recycling and admixing a 100 part of the hot waste heating gases with the hot products of combustion to reduce their temperature before passing the gaseous mixture in contact with the tubular surfaces of the still. 105

11. The improvement in the heating of tubular oil cracking stills in which oil is heated to the cracking temperature by hot products of combustion from a furnace passing externally over the tubular oil heating surfaces of the still, which comprises circulating the oil through the tubes in a generally upward direction, circulating the heating gases around the tubes in a generally downward direction, and recycling a part of the 110 hot waste heating gases and admixing them with the hot products of combustion from the furnace to lower the temperature of the hot products of combustion before passing them over the tubes. 115

12. The improvement in the heating of tubular oil cracking stills in which oil is heated to the cracking temperature by hot products of combustion from a furnace passing externally over the tubular oil heating surfaces of the still which comprises recycling a part of the hot waste heating gases and admixing them with the hot furnace gases before passing the gaseous mixture over the tubular heating surfaces, pro- 120 125 130

tecting the heating surfaces from direct radiation from the furnace and causing the recycled gases to be heated by radiation before the mixture of gases passes over the heating surface.

13. The improvement in the heating of tubular oil cracking stills in which oil is heated to the cracking temperature by hot products of combustion from a furnace passing externally over the tubular oil heating surfaces of the still, which comprises reducing the temperature of the heating gases first coming in contact with the tubes by admixture therewith of recycled hot waste heating gases and thereby obtaining a more uniform heating of the tubular still with increased velocity of flow of the gases.

14. The improvement in the heating of tubular oil cracking stills in which oil is heated to the cracking temperature by hot products of combustion from a furnace passing externally over the tubular oil heating surfaces of the still, which comprises diluting the heating gases with part of the hot waste heating gases, passing the resulting gaseous mixture over the tubes of the still in a series of passes and returning the hot gases after the last pass for admixture with the hot furnace gases.

15. The improvement in the heating of oil cracking stills in which oil is heated to the cracking temperature by hot products of combustion from a furnace passing externally over the oil heating surfaces of the still, which comprises admixing the hot gases from the furnace with returned hot waste heating gases from the still containing free oxygen before passing the gaseous mixture over the oil heating surfaces.

16. The improvement in the heating of tubular oil cracking stills in which oil is heated to the cracking temperature by hot products of combustion from a furnace passing externally over the tubular oil heating surfaces of the still, which comprises shielding the cracking tubes from direct radiation from the furnace and introducing recycled

hot waste heating gases from the still into the hot furnace gases before passing the gaseous mixture over the tubes of the still. 50

17. The improvement in the heating of oil cracking stills in which oil is heated to the cracking temperature by hot products of combustion from a furnace passing externally over the oil heating surfaces of the still, which comprises recirculating a part of the hot waste heating gases from the still over and through the furnace structure to cool the same and introducing the recirculated gases into the hot furnace gases before 60 passing the gaseous mixture over the oil heating surfaces.

18. The improvement in the heating of tubular oil cracking stills in which the oil is circulated from a bulk supply through 65 heating tubes and back to the bulk supply and in which the circulating oil is heated to the cracking temperature by hot products of combustion from a furnace passing externally over the heating tubes, which comprises recirculating a part of the hot waste heating gases from the still and admixing them with the hot products of combustion from the furnace to cool the same prior to passing the gaseous mixture over the heat- 70 ing tubes. 75

19. The improvement in the heating of tubular oil cracking stills in which the oil is circulated from a bulk supply through vertical heating tubes and back to the bulk supply and in which the circulating oil is heated to the cracking temperature by hot products of combustion from a furnace passing externally over the heating tubes, which comprises returning a part of the hot waste heating 80 gases from the still and admixing them with the hot products of combustion from the furnace to cool the same, and passing the resulting mixed gases in a generally downward direction and in a series of passes over the 85 heating tubes. 90

In testimony whereof I affix my signature.

JOHN E. BELL.
